UNITED STATES PATENT OFFICE

ALFRED RIDLEY, OF INDIANAPOLIS, INDIANA

CONCEALED HINGE

Application filed September 16, 1927. Serial No. 219,832.

This invention relates to improvements in doubly pivoted inserted concealed hinges for doors, lids, gates and the like, so as to enable the door and the like to be moved from the closed position 180° to the full open position or to any intermediate position.

The object of the invention is to provide hinges that are half inserted in the door and half inserted in the jamb or stationary member and arranged so that when the door is closed in alignment with the jamb the hinges are invisible and do not project outward beyond the door or jamb. To that end said hinges are made U-shaped and their ends are pivoted in corresponding metal sockets imbedded in adjacent surfaces of the jamb and door between the exposed outer faces of the jamb and door, and so that the walls of the sockets will positively stop and brace the various movements of the hinges as herein-after will more fully appear.

The full nature of the invention will be understood from the accompanying drawings and the following description and claim.

In the drawings Fig. 1 is a horizontal section through the hinge construction, and parts of a door and jamb, showing them in their position when the door is closed. Fig. 2 is a similar figure showing them in one position when the door is half open. Fig. 3 is a similar figure showing them in another position when the door is half open. Fig. 4 is a similar view showing their position when the door is entirely open 180° . Fig. 5 is an elevation of the same when the door is fully open, viewed from the line 5—5 of Fig. 4.

To illustrate this invention it is shown and associated with a door jamb 10 and a door 11, although the hinge may be associated with the lid of a box and the back wall of the box, or with a gate and a gate post. Two similar rectangular metal sockets 12 and 13 are inset in the adjacent portions of the jamb and door, considering the same when the door is closed or in alignment with the jamb, as seen in Fig. 1. The sockets are casings or boxes opening outward and having a flange 14 at the sides through which screws 15 are inserted for securing them in their recesses. The sockets are inserted between the outer and inner

walls of the door and jamb so that when the door is closed, as appears in Fig. 1, the brackets will not appear or be visible.

U-shaped links 16 are provided with their ends similarly shaped and pivoted by pivots 17 in the side walls of the sockets as shown. The edges of the link are straight except the extreme ends of the link are preferably rounded and concentric with the pivots, and the pivots are similarly located, as shown, and equi-distant from the two nearest wall surfaces adapted to be engaged by the link, so that in practically every position of the link member 16 a flat edge thereof will abut against a flat wall of each of the sockets which serves as stops for limiting any particular movement of the link member and its reinforcement, and also the rounded ends of the link will engage the adjacent walls.

In Fig. 1, wherein the door is closed, the lateral edge of each end of the link member abuts against the inner wall of a socket. In Fig. 2 the door is shown half open after having turned on the pivot 17 which is in the door, and then the inner edge of the hinge abuts against the outside wall of a socket while the other end of the link member remains in the position shown in Fig. 1, and that will limit the relative movement of the door and link member. Any further movement in opening of the door will swing it around to the open 180° position, shown in Fig. 4, where the inner edges of both ends of the link member snugly fit against the outer walls of both brackets and that limits the opening movement of the door. Or if the opening movement of the door from the position shown in Fig. 1 should turn on the jamb pivot 17 the hinge would assume the position shown in Fig. 3 where the inner edge of the link member abuts against the outer wall of the jamb member while the position of the parts in the door remain the same as in Fig. 1. Therefore, each link 16 in every position engages the socket walls at four places, as the rounded ends engage them at two points, and two side edges engage them.

Thus, it is seen that the door is limited in its various movements by the link member and sockets and does not depend on its en-

gagement with any other structure or with the jamb as the door never touches the jamb or wall with which the jamb is associated. The links 16 are relatively high, as shown in Fig. 5, and their upper and lower surfaces or walls rather snugly engage the upper and lower walls of the sockets 12 and 13. This feature, in addition to the stop construction above outlined, renders the hinge construction very strong and durable as well as invisible when the door is closed. Any number of hinge constructions can be applied to a door, but usually two or three suffice. These will prevent the door sagging and striking against jambs and walls of the building.

The hinge construction can be used with doors and the like in either a vertical position or a horizontal position and all corresponding parts of the hinge construction are of similar shape and dimensions so that they are interchangeable in either the right hand or left hand positions. While the various walls of the sockets and edges of the links are preferably straight and flat, they may be otherwise shaped.

The invention claimed is:

A hinge construction for doors and the like including metal sockets of similar three-sided rectangular shape and dimensions and similarly recessed with all corresponding walls thereof parallel with each other and adapted to be inset and secured in the adjacent portions of a jamb and door or the like, a rectangular U-shaped link with its portions of similar shape and dimensions and having parallel side edges and rounded ends, and with the upper and lower sides of the link fitting snugly in said sockets, and a pivot for pivoting each end of the link in its corresponding socket, the pivots being in the same relative positions in both sockets and so located near two adjacent walls that in all positions one flat edge of each end of the link will abut against one flat wall of the socket in which it is pivoted and its rounded end engage the adjacent wall of the socket, substantially as set forth.

In witness whereof, I have hereunto affixed my signature.
